UNITED STATES PATENT OFFICE.

SIMEON C. LAWLOR, OF CHICAGO, ILLINOIS.

CONTAINER-SUPPORT.

1,282,600.

Specification of Letters Patent.

Patented Oct. 22, 1918.

Application filed November 8, 1915. Serial No. 60,378.

To all whom it may concern:

Be it known that I, SIMEON C. LAWLOR, a citizen of the United States, residing at Chicago, in the county of Cook and State of Illinois, have invented certain new and useful Improvements in Container-Supports; and I do hereby declare the following to be a full, clear, and exact description of the invention, such as will enable others skilled in the art to which it appertains to make and use the same.

This invention relates to improvements in sustaining or supporting elements for containers, such as scrubbing pails and other vessels.

One of the objects in view is the provision of a shiftable support having means for detachably clamping or gripping a container and retaining the same in operative relation to the support.

With this and other objects in view as will in part hereinafter become apparent and in part be stated, the invention comprises certain novel constructions, combinations and arrangements of parts as will now be specified and subsequently pointed out in the appended claims.

In the accompanying drawing:

Figure 1 is a vertical section taken on the plane indicated by line 1—1 of Fig. 2, the container also being seen in section.

Fig. 2 is a top plan view thereof, the container being omitted, but indicated in dotted lines.

Fig. 3 is an enlarged detail sectional elevation of one of the clamping elements detached, parts being broken away.

Fig. 4 is a detail fragmentary perspective view of a slightly modified embodiment.

Fig. 5 is a detail cross sectional view taken on the plane indicated by line 5—5 of Fig. 4.

Fig. 6 is a view in side elevation of a slightly modified embodiment of the invention, parts being broken away as seen in section.

Fig. 7 is a plan view of the same, the container being indicated in dotted lines.

Fig. 8 is an enlarged detail, fragmentary, vertical section taken on the plane indicated by line 8—8 of Fig. 7.

Fig. 9 is a view in side elevation of a further modified embodiment, a fragment of a container being seen in section.

Fig. 10 is a view in front elevation of the part seen in Fig. 9, the upper portion of the

clamp being broken away and the container being omitted.

Figs. 2^a and 3^a are cross sections on lines 2^a, 2^a and 3^a, 3^a of Fig. 2.

Referring to the drawing by numerals, 1 indicates a support made up preferably of strips of material crossed and secured together in any appropriate manner as by a rivet 2 at the point of crossing. The strips making up the support 1 are preferably of heavy gage strap iron or other like appropriate material. The strips which form the support 1 in their radiation from a common center may be considered arms, and fixed to the support at the common center, as by being engaged by the rivet 2, is an additional arm 3 which is also preferably formed of a strip of material such as heavy gage strap iron. The arm 3 outstands radially from the central point approximately midway between two of the arms of support 1, and at its outer end portion is surrounded by a slidingly mounted sleeve 4, said sleeve being provided with a pin or rivet 5 extending through a slot 6 formed in the arm 3 so as to guide the sleeve 4 in its longitudinal movement. A spring 6' is fixed to the inner end portion of arm 3 and engages sleeve 4, by being connected to the pin 5, so as to exert pressure on the sleeve 4, tending to move the sleeve inwardly. The lower outer end portion of the sleeve 4 is bent downward to form a handhold or hook-shaped grip 7, and the upper outer end portion of the sleeve is bent to form an upstanding stop 8, which stop is curved to form a bead receiving corrugation 9. Obviously any shaping of the upturned portion 8 which produces a groove adapted to receive the bead of a bucket or other container, for instance as seen in Fig. 1, may be employed in lieu of the corrugation 9. Two of the arms formed of the strips making up support 1 terminate at 10, 10, and these two arms are those which with the arm 3 form a Y-shaped frame. Each of the arms terminating at 10 has its end portion inclosed by a slidingly adjustably mounted sleeve 11. A guiding pin 12 engages the terminal portion of each of the last named arms, and extends through a slot 13 in its respective sleeve 11. The pin 12, while shown in the form substantially as a rivet may be constructed in any desired manner, as for example, from the material of the re-

spective arm struck up through the slot 13. A clamping bolt 14 extends through the slot 13 at each sleeve 11, and through the respective arm and is provided with a wing nut 15 adapted to be threaded along the bolt for enabling adjustment of the sleeve 11 and for clamping the sleeve in its adjustable position. The outer end portion of each sleeve 11 is upturned to form a stop 16 similar in structure and function to the stop 8 and provided with a bead receiving corrugation or grooved portion 9' similar in form and function to the part 9. A plate 17 is fixed to the outer portion of each sleeve 11 as by 10 being riveted or otherwise appropriately connected thereto and each plate 17 is supported by a downwardly extending floor-engaging member, preferably in the form of a caster 18 which may be of the ordinary 15 conventional type. Each of the arms of support 1 opposite those engaged by slides or sleeves 11 is engaged by a slide or sleeve 19 and has a pin and slot connection therewith, the slot being preferably formed in 20 the respective arm as at 20, and the pin consisting of a bolt or other similar part 21, extending through the slot and through the sleeve 19 and engaged by a nut beneath the sleeve so as to be adapted for clamping the 25 sleeve 19 at any given adjustment longitudinally of the respective arm. Extending downwardly from the outer terminal portion of each slide or sleeve 19 is a floor engaging element consisting preferably of the 30 ordinary conventional caster 22.

The operation of the structure should be apparent and may be briefly stated to consist of sustaining a scrubbing bucket or other like receptacle by having the bottom 40 of the bucket fitted between the stops 8 and 16, and clamped thereby under the pressure of spring 6'. The ordinary scrubbing pail is provided with an annular bead at its base which is engaged by the grooved 45 portions 9 and 9', which effectively locks the bucket to the base 1 and prevents accidental dislodgment. The support 1 is thus a coaster for the sustained receptacle and greatly facilitates shifting of the same about the floor.

50 Ordinarily, the stops 8 and 16 are sufficient for preventing dislocation of the supported receptacle but as a further precaution against relative movement of the bucket with respect to the support, there are provided clamping apparatus designed to engage the upper edge of the receptacle and to clamp the same down against the support. Each of such clamping apparatus consists of a connecting rod 23 having a 55 hook 23' at its upper end designed to engage the upper edge of the receptacle. The lower end of rod 23 is provided with a pair of eyes, each engaged by a coil spring 24, each of which spring structures depends 60 from the rod 23 and is provided at its lower

end with a hook 25 designed to engage an eye in the respective stops 8 and 16. As two springs 24 are employed, each of said stops is preferably provided with two eyes.

In Figs. 4 and 5 is illustrated a slightly 70 modified form of connection between the supporting caster and the arms forming the main support. 1^a, 1^a are the arms of said support with the additional arm 3^a fixed together by the central rivet 2^a. In lieu of the 75 forms of connections of the casters to the arms just above described, a caster 18^a is pivotally connected to a plate 17^a which is inclosed by a sleeve 19^a also surrounding the outer portion of the respective arm 1^a. The 80 sleeve 19^a and arm 1^a are provided with registering longitudinal slots 20^a through which extends a bolt 21^a, said bolt also extending through an aperture in a plate 17^a, and its lower end portion being engaged by 85 a wing nut 21'. The sleeve 19^a is open, as are all of the sleeves above described, and the nut 21' seats directly against plate 17^a, so that by tightening up the nut, plates 17^a and the arm 1^a can be clamped together and 90 the caster thus locked to the support member in any given adjusted position. The outer terminus of the sleeve 19^a is formed with an upturned stop portion 16^a which is identical in form and function with stop 16. 95

The structure seen in Figs. 6, 7 and 8 differs from that seen in Fig. 1, chiefly in the fact that the arms forming the support have their outer ends connected by a stiffening ring.

100 With this in mind and referring particularly to Figs. 6, 7 and 8, the structure therein seen will be observed to consist of a support formed of radial arms 31, 31, 32, 32, and an interposed arm 33, and connected 105 centrally by a rivet 34. The outer end portion of each of said arms is bent upwardly at 35 and formed into an eye 36, surrounding a ring 37. Ring 37 may be of any appropriate material, but is preferably a 110 metallic rod, and is designed particularly to prevent any dislocation of the arms relative to each other. The arms 32 are engaged by sleeves 38, each having a stop 39, and each being formed with a longitudinal slot 115 40, through which a bolt 41 is passed, which bolt 41 extends through the respective arm 32, engaged by sleeve 38 and a nut 42 is threaded on to the respective bolt 41 beneath the arm so as to enable clamping of 120 the sleeve 38 at any desired point of adjustment. The sleeve 38 is open underneath the engaged arm, and in fact, may be constructed in the form of a simple sliding plate. The outer portion of each arm 32 is 125 engaged and sustained by a caster 43, and the outer portion of each of the arms 31 is similarly engaged by a similar caster 43. The arm 33 is engaged by a sleeve 44 having a pin and slot connection with the arm 33, 130

and being engaged by a spring 45, connected to the inner portion of the arm and tensioned to draw the sleeve or slide 44 inward. The outer end of the slide or sleeve 44 is provided with an upstanding stop 39', the several stops 39 and 39' being the same in structure and function as the stops 16 and 8. Depending from the sleeve 44 is a curved grip or handle 46, adapted to be grasped by the operator for drawing the sleeve 44 outward against the tension of spring 45, when a receptacle is to be introduced between the stops 39, 39, and 39'. In practice, a receptacle is positioned merely by drawing the sleeve 44 outward and placing the receptacle upon the supporting arms 31 and 32, with the bead of the receptacle engaging the groove of the stops 39, the slide 44 having been drawn outward enough to clear the receptacle, and after it has been positioned in engagement with the stops 39, the sleeve 44 is released and the stop 39' thus caused to engage the receptacle under the tension of spring 45. It is obvious that this is the same operation as that employed in applying the receptacle to the structures seen in Figs. 1 and 2. Receptacle retaining stays may be employed in this construction identical with those seen in Fig. 1, each consisting of the rod 23 and springs 24 and their connected parts. Preferably these stays in this construction are arranged with one of the springs in engagement with one of the respective stops and with the other spring in engagement with the ring 37.

In Figs. 9 and 10, I have shown a further modification, in which the major portion of all of the arms is eliminated and only a short section of plate 51 is employed for each caster 52. Upon each plate 51 is fixed a plate 53, having an upstanding portion 54, the plates 51 and 54 being formed with bent portions 55 and 56, respectively, for forming a bead receiving groove for the receptacle. Fixed to the upstanding portion 54 is a sleeve 57, through which extends a stay rod 58, having a hook 59 at its upper end adapted to engage the upper end of the receptacle. The lower end of stay 58 is engaged by an adjusting nut 60, and a coil spring 61 is interposed between the nut 60 and the sleeve 57 and tensioned to pull downwardly on the rod 58 for producing a clasping or gripping action by the hook 59 in coöperation with the parts 55 and 56. As many of the supporting elements 51 and connecting parts are provided for a bucket as preferred, three being sufficient, but four being preferably used and a greater number may be supplied where the receptacle is relatively large.

What I claim is:—

1. In a device of the class described, the combination of a series of arms connected centrally and outstanding radially from the

central point, supports for the arms, stops movably carried by some of said arms, and a spring pressed stop movably carried by one of said arms in position for coöoperating with the other stops for clamping a container therebetween. 70

2. In a device of the class described, the combination with arms connected to form a support, slides engaging some of said arms, means for adjustably retaining the slides 75 in various positions, container engaging stops extending from the slides, a spring pressed slide movably sustained by one of the arms, and a container engaging stop extending from the last mentioned slide in 80 position for pressing a container toward the other stops.

3. In a device of the class described, the combination of supporting arms, slides engaging said arms and having pin and slot 85 connections therewith, stops carried by the slides, a spring pressed slide carried by one of the arms in position for coöoperating with the other slides, and a stop carried by the spring pressed slide. 90

4. In a device of the class described, strips of material disposed across each other and connected centrally for forming radially outstanding arms, an arm also connected centrally with the first mentioned arms and 95 outstanding between two of the first mentioned arms, a stop carried by the last mentioned arm, and stops carried by two of the first mentioned arms in position for coöperating with the first mentioned stop for engaging a receptacle. 100

5. In a device of the class described, strips of material disposed across each other and connected centrally for forming radially outstanding arms, an arm also connected centrally with the first mentioned arms and outstanding between two of the first mentioned arms, and stops carried by the last mentioned arm and two of the first mentioned arms in position for coöperating for engaging a receptacle, one of the stops being movable and spring pressed. 105 110

6. In a device of the class described, the combination of supporting arms, means for clasping a container resting on said arms, 115 and casters sustaining said arms, some of said casters being shiftable longitudinally of the arms.

7. In a device of the class described, the combination of supporting arms, means for 120 clasping a container resting on said arms, the said means being adjustable, and supporting casters for the arms, one of said casters being movable relative to the arms.

8. A container support comprising arms 125 adapted to be disposed beneath a container, container engaging means sustained by the arms, one of said means being adjustable relative to others for engaging containers of different dimensions, supporting means for 130

the arms extending below the same, one of the supporting means being movable longitudinally and independently of one of the arms, and a spring engaging the movable supporting means and tensioned to be stressed during independent movement of the supporting means.

Copies of this patent may be obtained for five cents each, by addressing the "Commissioner of Patents, Washington, D. C."

In testimony whereof I affix my signature in presence of two witnesses.

SIMEON C. LAWLOR.
